[57] CLAIM

The ornamental design for a casserole for a microwave
oven, substantially as shown.

DESCRIPTION

FIG. 1 is an exploded side elevational view of a casserole
for a microwave oven, showing my new design;
FIG. 2 is an exploded view thereof as seen along a
central vertical section through FIG. 1;
FIG. 3 is a top plan view thereof;
FIG. 4 is a bottom plan view thereof; and
FIG. 5 is an enlarged fragmentary perspective view of
the fluted central portion.

FIG. 3

FIG. 4

FIG. 5
